UNITED STATES PATENT OFFICE.

RICHARD W. TANNER, OF ALBANY, NEW YORK.

PEDAL-GUARD FOR PIANOS.

SPECIFICATION forming part of Letters Patent No. 309,006, dated December 9, 1884.

Application filed March 4, 1884. (No model.)

To all whom it may concern:

Be it known that I, RICHARD W. TANNER, a citizen of the United States, residing at Albany, in the county of Albany and State of New York, have invented a new and Improved Pedal-Guard for Pianos, of which the following is a specification.

My invention relates to a pedal-guard for pianos in which are employed two pieces, one for secure attachment to the pedal-bar and provided with dovetail tongues, and the other attachable to and detachable from the attached piece; and it consists in one part of a guard-plate provided with perforations for its secure attachment to the pedal-bar of a piano, and with dovetail tongues projecting upward from the upper edge of said plate to adapt the same to hold with a detachable guard-bar, and in another part of a guard-bar provided with dovetail lips to adapt the bar to be readily attached to the guard-plate; and, further, it consists of the combination, with a guard-plate adapted to have secure attachment to the wooden work of a piano at its pedals, and provided with dovetail tongues, of a guard-bar which is provided with dovetail lips which engage with the dovetail tongues of the guard-plate to hold the former in connection with the latter.

The objects of my invention are to provide means for protecting the polished wood of a piano at the vicinity of its pedals from being marred by the shoes or slippers on either small or large feet of operators, and to render detachable the upper portion of the pedal-guard, so that it may be readily removed at will for cleaning or polishing. I attain these objects by means of the devices illustrated in the accompanying drawings, in which—

Figure 1 represents a front view of the detachable guard-bar. Fig. 2 is a view of the same from below, with guard-plate shown with edgewise view. Fig. 3 is a front view of the guard-plate. Fig. 4 is a view of a pedal-bar from its upper side with guard-plate secured therewith. Fig. 5 is a cross-sectional view of pedal-bar, pedal-plate, and guard-bar when said parts or devices are arranged together for operation, and Fig. 6 is a front view of the same.

The same letters of reference refer to like parts throughout the several views.

In the drawings, A represents the guard-plate, and B is the guard-bar. The guard-plate A is made in the form of a thin flat piece 55 of metal made with a width from about two or two and one-half inches and a length of about seven inches, more or less, or sufficient other length to cover over an extent of surface of the wood of the piano against which the foot of the 60 operator will usually touch when operating pedals P P. This plate is provided with pedal-recesses a a, extending upward from its lower edge to a distance of about one and one half inch, and are located in the plate at 65 such a distance apart as will correspond with the distance between pedals P P, as shown in Fig. 6. These recesses are made with a width of opening a little greater than the width of the pedals, so that the latter will not touch the 70 side edges of the former when being operated. Made with the upper portion of this guard-plate, at about its middle of length, is ear b, which is provided with perforations c. This plate is also provided with perforations c' c', 75 which are countersunk to receive the screws which are countersunk to receive the screws for attaching the plate to pedal-bar D, to which pedals P P are pivoted. Projecting from the upper edge of this guard-plate, from points near the ends thereof, are dovetail tongues d 80 d, Figs. 2, 3, and 6.

The guard-bar B consists of a short bar of metal provided with dovetail lips e e, Fig. 2, set equidistant from the middle of the length of the bar, and at a distance apart corresponding with dovetail tongues d d, so that the latter will engage with the former, as shown in Figs. 2 and 6. Made with this bar, at its middle of length, is ear f, which is situated between dovetail lips e e, corresponding with the 90 situation of ear b, between dovetail tongues d d. This ear f is pierced with hole m, corresponding with perforations c in the guard-plate.

Both the guard-plate and guard-bar may be 95 made plain or ornamental, as may be preferred.

The guard-plate A is secured to pedal-bar D by screws s s, passing through perforations c' c', with recesses a a at the usual pedal-openings in the pedal-bar. The guard-bar B is then placed in position on the guard-plate, with the dovetail tongues d d of the latter engaging with the dovetail lips e e of the former, as shown in

Figs. 2 and 6, when perforated ear *f* of bar B will be in situation over perforated ear *b* of plate A. A screw, *s'*, will then be passed through perforations *f* and *b* and screwed into the wood of pedal-bar D, when guard-bar B will be securely held in connection with guard-plate A, as pedal-bar D, yet be readily detachable by removal of a single screw, *s'*, when it is desired to clean or polish up said bar in all its parts without touching the polish of the wood of the piano. If preferred, the perforated ear *b* may be omitted from guard-plate A, and screw *m* may be passed only through perforated ear *f* of bar B and screwed into the wood. When these two devices—plate A and bar B—are in place, plate A operates to prevent the shoes or slippers on small feet of an operator from touching the polished wood of the piano, while the said plate, together with bar B, operates to prevent those on the larger feet of an operator from touching the wood-work when operating the pedals. If preferred, perforated ear *b* on plate A and perforated ear *f* on bar B may be omitted when the dovetail tongues and lips are made to tightly engage with each other.

I am aware that plates provided with recesses through which the pedals work and secured to the pedal-bar of a piano are old; but such plates were not adapted to operate to hold a guard-bar in connection with the pedal-bar of a piano. I therefore do not claim such old plates as my invention.

I am also aware that metal bars have been used with pedal-bars by being secured directly to the same; but such bars were not adapted

to guard the polished-wood surface at the pedals from being injured by the shoes or slippers of children or other operators having small feet, and could not be readily removed for being polished. I therefore do not claim such old bars as my invention. 40

What I claim, and desire to secure by Letters Patent, is—

1. The guard-plate A, provided with perforations *c' c'*, for secure attachment to the pedal-bar of a piano, and having pedal-recesses *a a* in its lower portions, and provided with dovetail tongues made upon the upper edge portion of said plate, substantially as 45 and for the purposes set forth.

2. The guard-bar B, provided with perforated ear *f*, and dovetail lips *e e*, constructed and arranged substantially as above described, for operations and purposes set forth. 55

3. The combination, with guard-plate A, having means for its attachment to a pedal-bar and provided with dovetail tongues *d d*, of guard-bar B, provided with dovetail lips *e e*, substantially as and for the purposes set 60 forth.

4. The combination, with pedal-bar D of a piano, of guard-plate A, securely attached to said bar and provided with dovetail tongues *d d*, and the guard-bar B, provided with dovetail lips *e e*, and perforated ear *f*, all substantially as and for the purposes set forth. 65

RICHARD W. TANNER.
